METHOD OF ENLARGING A WOOD HOUSE

Ellis Jones, 1105 28th St., Galveston, Tex.

Filed June 10, 1960, Ser. No. 35,239

5 Claims. (Cl. 20—5)

The present invention relates to houses generally and in particular to the method of enlarging a wood house having a gable roof.

In the housing industry, it frequently becomes necessary to enlarge a wood house having a gable roof so as to provide more living space within the house. Previous methods proposed have included separating portions of the house outwardly from each other and constructing interior or interposed parts between the separated portions of the house. It has been difficult in the past to enlarge a gabled roof house without completely removing the roof therefrom when a sidewall of the house is moved outwardly.

An object of the present invention is to provide a method for enlarging a house having a gable roof which is accomplished with ease and facility and without disturbing a major portion of the roof structure, ceiling structure, or floor structure.

Another object of the present invention is to provide a method of enlarging a house constructed of wood and having a first floor ceiling which includes enlarging and extending the ceiling outwardly after a sidewall of the house has been moved without the need for erecting supporting partitions under the original ceiling.

A further object of the present invention is to provide a method of enlarging a wooden house which is commercially practical, one accomplished with a minimum of skilled labor, and one which is highly effective in action.

These and other objects and advantages of the present invention will be fully apparent from the following description when taken in conjunction with the annexed drawings, in which:

Figure 1 is an end elevational view of a wooden house showing the first step in shifting one sidewall of the house outwardly.

Figure 2 is a side elevational view with portions broken away and on an enlarged scale of the assembly shown in Figure 1.

Figure 3 is a view taken on the line 3—3 of Figure 2, the dotted line shown indicating the new position of the sidewall.

Figure 4 is a view on an enlarged scale, taken on the line 4—4 of Figure 2.

Figure 5 is a view of the assembly shown in Figure 4 as viewed from one side.

Figure 6 is a view on an enlarged scale, taken on the line 6—6 of Figure 2.

Figure 7 is a view of the assembly shown in Figure 6, as viewed from one side, and

Figure 8 is a fragmentary view taken on the line 8—8 of Figure 7.

Referring in greater detail to the drawings, in which like numerals indicate like parts throughout the several views, in Figures 1 to 3, the reference numeral 10 designates generally a house constructed of wood and including sidewalls 12 and 14 and a gable roof 16 extending over the sidewalls 12 and 14, and at least one end wall

2

18 connecting the adjacent ends of the sidewalls 12 and 14 together.

The house 10 includes side foundation members 20 and 22 and a central foundation member 24. The foundation members support floor joists 26 and the sidewalls 12 and 14 support ceiling joists 28.

Employed in the method of the present invention, the house 10 is to be enlarged by moving the sidewall 14 outwardly from the full line position in Figure 3 to the 10 dotted line position. This is accomplished by first separating the ceiling joists 28 and the floor joists 26 inwardly of and adjacent the sidewalls 14 and the roof 16 at the apex point to form a separated unitary sidewall and roof section, designated generally by the reference numeral 15 30.

Before severing the roof 16, two brace structures 32 and 34 are attached to the underface of each section of the roof, as in Figure 3. The structure 34 includes a horizontal member 36, a plurality of vertical members 20 38, and a plurality of angularly disposed members 40.

The upper end of the brace structure 34 is secured to a plate member 42 which is temporarily fastened on the under faces of the roof rafters 44. The lower end of the brace structure 34 is mounted upon spaced rollers 25 46 temporarily nailed to the upper faces of the ceiling joists 28.

Each roller 46 is supported upon an elongated shaft 48 which extends between the legs 50 of an upstanding U-shaped support element 52. The support element 52 has its bight 54 provided with a plurality of holes 56 for receiving therethrough nails 58 for securing the element on the ceiling joists 28, as shown most clearly in Figure 7.

The sidewall 14 has been prepared by removal of a 35 portion of the siding 60 and fastening of stringers 62 and 64 over the inner and outer faces of the wall studs 66 at a point spaced above the sill 68.

Next, a floor joist extension structure, designated generally by the reference numeral 70, is positioned so that 40 one end abuts the severed ends of the floor joists 26, and preferably extends between adjacent floor joists 26 for a distance inwardly of the wall 14. The extension structure 70 includes at least two beams 72 and 74 resting upon the foundation member 22 and having their 45 free ends supported upon an auxiliary foundation member 76, as shown in Figure 3.

With reference to Figures 4 and 5, a roller jack assembly 78 is now inserted upon the beams 72 and 74 with the upper end of the jack 80 bearing against the under 50 face of a plate member 82 which has been inserted under and secured to the lower edges of the stringers 62 and 64.

The roller jack assembly 78 includes four rollers 84 mounted upon opposite ends of shafts 86 which have 55 their intermediate parts extending through sleeves 88 formed in the bottom of the jack 80.

The studs 66 are now detached from the sill 68 and the screw part of the jack 80 is rotated by the handle 90 to raise the stringers 62 and 64 and the attached side- 60 wall 14 upwardly a distance sufficient to disconnect the studs 66 from the sill 68.

Next, the unitary section 30 including the rafters 44, shingles and the brace structure 34, together with the wall 14 are shifted laterally outwardly from the original 65 position to a point adjacent the other ends of the beams 72 and 74, as shown in dotted lines in Figure 3.

Next the apex portion or point of the separated roof section is secured to the severed apex point of the roof by providing between the two separated points decking or 70 other roof structure, as at 92 in Figure 3.

Finally, a new sill is mounted upon the new floor joists provided by the beams 72 and 74 and other joists inserted

between them and the wall 14 has its studs 66 secured to the new sill. Other ceiling joists are inserted between the existing ceiling joists and secured thereto so as to continue the ceiling structure between the severed ends of the ceiling joists 28.

Next, the rollers 46 and the roller jack assembly 78 is removed, together with the brace structure 34 and finally other siding is employed to fill in the space between the unitary side wall and roof section 30 and the existing house structure.

A preferred form of the means for moving the section 30 outwardly of the house 10 is shown in Figure 3 and consists in a block and tackle assembly 94 having one end temporarily attached to an upright 96 and the other end attached to the adjacent stringer 64.

It will be noted that the rollers 84 are connected to the jack assembly 78 by means of U-bolts 85. The rollers 84 may be detached from the housing 87 of the assembly 78 and the jack assembly 78 used without the rollers 84.

What is claimed is:

1. The method of enlarging a house constructed of wood and including a side wall and a gable roof which comprises separating the ceiling joists and the floor joists inwardly of and adjacent said sidewall and the roof at the apex point to form a separated unitary sidewall and roof section, attaching a brace structure to the under face of said roof section, movably supporting said brace structure on the ceiling joists, placing a floor joist extension structure so that one end abuts the severed end of said floor joists and projects laterally outwardly from said side wall, movably supporting said side wall on said floor joist extension structure, shifting said section with the attached brace structure outwardly along said joist extension structure to a point adjacent the other end thereof, connecting the apex point of said separated roof section with the severed apex point of said roof, eliminating the movable support of said brace structure on the ceiling joist and of said side wall on said floor joist extension structure, and filling in the space between said unitary side wall and roof section and said house with siding.

2. The method of enlarging a house constructed of wood and including a side wall and a gable roof which comprises separating the ceiling joists and the floor joists inwardly of and adjacent said sidewall and the roof at the apex point to form a separated unitary sidewall and roof section, attaching a brace structure to the under face of said roof section, rotatably supporting said brace structure on the ceiling joists, placing a floor joist extension structure so that one end abuts the severed end of said floor joists and projects laterally outwardly from said side wall, rotatably supporting said sidewall on said floor joist extension structure, shifting said section with the attached brace structure outwardly along said joist extension structure to a point adjacent the other end thereof, connecting the apex point of said separated roof section with the severed apex point of said roof, eliminating the movable support of said brace structure on the ceiling joists and of said side wall on said floor joist extension structure, and filling in the space between said unitary side wall and roof section and said house with siding.

3. The method of enlarging a house constructed of wood and including a side wall and a gable roof which comprises separating the ceiling joists and the floor joists inwardly of and adjacent said sidewall and the roof at

the apex point to form a separated unitary sidewall and roof section, attaching a brace structure to the under face of said roof section, movably supporting said brace structure on the ceiling joists, placing a floor joist extension structure so that one end abuts the severed end of said floor joists and projects laterally outwardly from said side wall, movably supporting said side wall on said floor joist extension structure, shifting said section with the attached brace structure outwardly along said joist extension structure to a point adjacent the other end thereof, connecting the apex point of said separated roof section with the severed apex point of said roof with a decking extending from the separated roof section apex point to the severed apex point of said roof, eliminating the movable support of said brace structure on the ceiling joists and of said side wall on said floor joist extension structure, and filling in the space between said unitary side wall and roof section and said house with siding.

4. The method of enlarging a house constructed of wood and including a side wall and a gable roof which comprises separating the ceiling joists and the floor joists inwardly of and adjacent said sidewall and the roof at the apex point to form a separated unitary sidewall and roof section, attaching a brace structure to the under face of said roof section, movably supporting said brace structure on the ceiling joists, placing a floor joist extension structure so that one end abuts the severed end of said floor joists and projects laterally outwardly from said side wall, movably supporting said side wall on said floor joist extension structure, shifting said section with the attached brace structure outwardly along said joist extension structure to a point adjacent the other end thereof, connecting the apex point of said separated roof section with the severed apex point of said roof with a decking of inverted V-shaped construction and extending from the separated roof section apex point to the severed apex point of said roof, eliminating the movable support of said brace structure on the ceiling joists and of said side wall on said floor joist extension structure, and filling in the space between said unitary side wall and roof section and said house with siding.

5. The method of enlarging a house constructed of wood and including a side wall and a gable roof which comprises separating the ceiling joists and the floor joists inwardly of and adjacent said sidewall and the roof at the apex point to form a separated unitary sidewall and roof section, attaching a brace structure to the under face of said roof section, rotatably supporting said brace structure on the ceiling joists, placing a floor joist extension structure so that one end abuts the severed end of said floor joists and projects laterally outwardly from said side wall, rotatably supporting said sidewall on said floor joist extension structure, shifting said section with the attached brace structure outwardly along said joist extension structure to a point adjacent the other end thereof, connecting the apex point of said separated roof section with the severed apex point of said roof with a decking of inverted V-shaped construction and extending from the separated roof section apex point to the severed apex point of said roof, eliminating the movable support of said brace structure on the ceiling joists and of said sidewall on said floor joist extension structure, and extending the ceiling joists and said floor joists.
